Specification for Design.

Patented Aug. 8, 1922.

Application filed November 16, 1921. Serial No. 515,722. Term of patent 7 years.

To all whom it may concern:

Be it known that I, MARCUS STERN, a citizen of the United States, residing in the borough of Brooklyn, county of Kings, city and State of New York, have invented a new, original, and ornamental Design for a Tray, of which the following is a specification, reference being had to the accompanying drawings forming part thereof.

Referring to the drawings, Figure 1 is a side plan view of a tray showing my new

design; Figure 2 is a top plan view of the same; Figure 3 is an end plan view from the front; and Figure 4 is an end plan view from the rear.

I claim:

The ornamental design for a tray as shown.
